UNITED STATES PATENT OFFICE.

ROBERT S. ASPINWALL, OF CLEVELAND, OHIO, ASSIGNOR TO THE VIRDEN MANUFACTURING COMPANY, OF CLEVELAND, OHIO, A CORPORATION OF OHIO.

SUSPENSION-LOOP FOR ELECTRIC FIXTURES.

1,012,582.

Specification of Letters Patent. Patented Dec. 26, 1911.

Application filed May 15, 1911. Serial No. 627,141.

To all whom it may concern:

Be it known that I, ROBERT S. ASPINWALL, a citizen of the United States, residing at Cleveland, in the county of Cuyahoga and State of Ohio, have invented a certain new and useful Improvement in Suspension-Loops for Electric Fixtures, of which the following is a full, clear, and exact description.

10 This invention is a novel form of loop especially adapted for use in flexibly suspending electric lighting fixtures, or to form a part of means for flexibly suspending such electric lighting fixtures.

15 The object is to provide a good looking and comparatively cheap loop through which the electric conductor may be easily passed, and which may conveniently be connected with and disconnected from the part, 20 from which it is to hang or the part which is to hang from it.

In the drawing, Figure 1 is an elevation of a completed loop. Fig. 2 is a central longitudinal section thereof; and Fig. 3 is a 25 transverse section in a plane indicated by line 3—3 on Fig. 2.

Each loop in which the invention is embodied is composed of three independently made pieces, viz: the body piece A, a split ring B and a tubular thimble C. The body piece has a longitudinal hole a through it from end to end; and this hole is threaded from one end more or less nearly half way through to the other end. In each body piece also are two diametrically opposed ring sockets a'.

The ring B is split and is preferably made of spring metal. Its ends are bent so that for a short distance they are more or less nearly straight and well nigh in alignment with each other, and are separated sufficiently far to enable them to be sprung apart and inserted into the ring sockets a.

The tubular thimble C is externally threaded from end to end, so that one end may be screwed into the body piece, while the other end is adapted to be screwed into whatever the loop is to be connected with.

There are several advantages of the construction. The electric conductor has to pass through the hole in the loop and thimble,—and since the suspending ring can be turned down to the side, it is easy to thread the conductor through this hole; moreover, the loop may be connected with a suspending chain or the like by springing the ring out of its socket at one side or the other.

The thimble is to be screwed into some part of the electric device, and this may be done and the loop screwed up tight because the threads on the thimble go close up to the body. If the thimble were made a part of the body it is well nigh impossible to carry the threads thereon up to the body. This thimble, as shown, being without shoulders or other complications, may be made in an automatic screw machine through which a tube of indefinite length will be automatically fed, and after being threaded, suitable lengths will be cut off, and the thimble produced may be screwed into the body.

Having described my invention, I claim:

1. In a loop for electric lighting fixtures, the combination of a tubular body which is internally threaded part way through, with an externally threaded tubular thimble screwing into said body piece, and a suspension ring connected with said body piece.

2. In a loop for electric lighting fixtures, the combination of a tubular body piece, which is internally threaded from one end, an externally threaded tubular thimble which screws into said body piece, and a split ring, said body piece being provided near its unthreaded end with diametrically opposed sockets which receive the ends of said split rings.

In testimony whereof, I hereunto affix my signature in the presence of two witnesses.

ROBERT S. ASPINWALL.
